(57) **CLAIM**

The ornamental design for the pressure washer with retractable handle, as shown and described.

DESCRIPTION

FIG. 1 is a front right perspective view of a pressure washer with retractable handle in a retracted position;

FIG. 2 is a right side view of the pressure washer with retractable handle in a retracted position;

FIG. 3 is a front view of the pressure washer with retractable handle in a retracted position;

FIG. 4 is a left side view of the pressure washer with retractable handle in a retracted position;

FIG. 5 is a rear view of the pressure washer with retractable handle in a retracted position;

FIG. 6 is a top view of the pressure washer with retractable handle in a retracted position;

FIG. 7 is a bottom view of the pressure washer with retractable handle in a retracted position;

FIG. 8 is a front right perspective view of the pressure washer with retractable handle in an extended position;

FIG. 9 is a right side view of the pressure washer with retractable handle in an extended position;

FIG. 10 is a front view of the pressure washer with retractable handle in an extended position;

FIG. 11 is a left side view of the pressure washer with retractable handle in an extended position;

FIG. 12 is a rear view of the pressure washer with retractable handle in an extended position; and

FIG. 13 is a top view of the pressure washer with retractable handle in an extended position; and,

FIG. 14 is a bottom view of the pressure washer with retractable handle in an extended position.

The broken lines in FIGS. 6 and 13 are for illustrative purposes only, and form no part of the claimed design.
